UNITED STATES PATENT OFFICE

154,937

DESIGN FOR A SCOOP FOR DISPENSING ICE CREAM OR THE LIKE

Howard V. Lindbergh, Lafayette, Calif.

Application September 11, 1947, Serial No. 141,312

Term of patent 14 years

(Cl. D44—29)

To all whom it may concern:

Be it known that I, Howard V. Lindbergh, a citizen of the United States, residing at Lafayette in the county of Contra Costa, State of California, have invented a new, original, and ornamental Design for a Scoop for Dispensing Ice Cream or the like, of which the following is a specification:

Reference is had to the accompanying drawing forming a part hereof, in which:

The essential features of the design reside in those portions shown in full lines.

I claim:

The ornamental design for a scoop for dispensing ice cream or the like, as shown and described.

HOWARD V. LINDBERGH.
